UNITED STATES PATENT OFFICE.

PHILIP C. TRAVER, OF LYNBROOK, NEW YORK, ASSIGNOR OF ONE-THIRD TO GEORGE E. WIEDNER AND ONE-THIRD TO LESLIE J. EKENBERG, BOTH OF FAR ROCKAWAY, NEW YORK.

AIRSHIP.

Application filed February 6, 1928. Serial No. 252,262.

The present invention relates generally to lighter than air craft and more particularly to air ships of the dirigible type using a bag containing a lighter than air gas such as 5 helium, hydrogen, and the like.

The prime object of the invention resides in the provision of an air ship of this nature comprising a skeleton like casing or frame for containing the gas bag to afford protection thereto and to maintain the same in a 10 substantially ellipsoidal shape for withstanding air pressures to which a craft of this nature is subjected in use and thereby prevent the usual distortion.

15 A further important object of the invention resides in the provision of an air ship of this nature which may be built at a comparatively low cost, is strong and durable, and thoroughly efficient and reliable in operation.

With the above and numerous other objects in view as will appear as the description proceeds, the invention resides in certain novel features of construction, and in the combination and arrangement of parts as will be 25 hereinafter more fully described and claimed.

In the drawing:

Figure 1 is a side elevation of an air ship embodying the features of my invention,

30 Figure 2 is a vertical longitudinal section therethrough,

Figure 3 is a vertical transverse section on an enlarged scale taken substantially on the line 3—3 of Figure 2,

35 Figure 4 is a fragmentary longitudinal section through one nose portion of the gas bag, and

Figure 5 is a perspective view of the front elevator.

40 Referring to the drawing in detail, it will be seen that the frame work comprises curved longitudinal members 5 connected intermediate their ends by a band 6. The members 5 converge forwardly and rearwardly from their centers toward their ends and are joined together at said ends. Frusto-conical end members 7 have their larger ends extending a distance over the ends of the longitudinal members 5 and are welded or otherwise suitably secured thereto. Prime movers 8 are mounted in the end members 7 for driving shafts 9 journaled through the smaller

ends of the members 7 for operating propellers 10. The propeller 10 at the front is of the pull type and that at the rear is of 55 the push type. Cross members 11 are disposed in the members 7.

A fuselage or housing 12 is suspended from the framework and has suitable provisions for accommodating a number of passengers 60 as well as the necessary crew. Landing wheels 13 are journaled on axles 14 across the bottom of the housing 12.

The gas bag is disposed in the frame work and the preferred embodiments thereof comprises a bladder 15 of rubber or other like elastic material. A leather casing 16 receives the bladder 15 and has one or more laced openings 17 so that the bladder may be inserted therein and removed therefrom. The 70 gas bag is ellipsoidal in formation to provide two ends or noses which are covered by asbestos packing 18, said packing being covered by a metal nose 19. Rivets or other securing devices or means 20 are used for securing the 75 nose 19 and the packing 18 on the casing 16.

Bolts 20 project outwardly from the apexes of the noses 19 through openings in the end junctures of the members 5 and through openings in cross members 11 and nuts 21 are 80 threaded thereon so that the gas bag may be securely held in the frame work and the ends of the bag pulled to maintain the gas bag in its proper shape thereby preventing the gas bag from coming out of the frame work and 85 preventing any great distortion thereof due to air pockets, air pressures, and the like to which the air ship will be subjected in actual use.

Any suitable controls may be used for 90 maneuvering the air ship. It is preferred, however, to hinge upper and lower elevators 25 and 26 respectively to the rear end member 7 with suitable means 27 associated therewith so that the elevators may be swung upwardly or downwardly. Rudders 28 are hingedly mounted on the rear end member to the sides thereof and are controlled by suitable means 29. An elevator 30 is hingedly mounted intermediate its ends as at 31 on 95 brackets 32 depending from the forward portion of the end member 7. A guide 33 extends downwardly from the end member 7 adjacent the rear free edge of the elevator 30.

This elevator 30 is provided with cranks 34 which are controlled by suitable means 35 for swinging the elevator. The forward portion of the elevator has a downward curve 6 as is indicated specifically at 36.

The end members as well as the housing are preferably constructed of aluminum or duraluminum or any other equivalent light metal.

10 It is thought that the construction, operation and advantages of the invention have been disclosed with sufficient particularity so that those skilled in this art will thoroughly understand the construction, operation 15 and advantages thereof.

The present embodiment of the invention has been disclosed in detail merely by way of example since in actual practice it will attain the features of advantage enumerated 20 as desirable in the statement of the invention and the above description. It will be apparent that changes in the details of construction, and in the combination and arrangement of parts may be resorted to without departing from the spirit or scope of the 25 invention as hereinafter claimed or sacrificing any of its advantages.

Having thus described my invention, what I claim as new is:

30 1. An airship of the class described comprising a frame work of an ellipsoidal formation, frusto-conical end members having their larger ends overlapping the ends of the framework and secured thereto, a gas bag disposed in the framework, and means for adjustably anchoring the ends of the gas bag to the end members.

40 2. An air ship of the class described comprising a frame work of an ellipsoidal formation, frusto-conical end members having their larger ends overlapping the ends of the frame work and secured thereto, propellers at the smaller ends of the end members, means for operating the propellers from the interior of 45 the end members, and a gas bag disposed in the frame work, and means for adjustably anchoring the ends of the gas bag to the end members.

50 3. An air ship of the class described comprising a frame work of an ellipsoidal formation, frusto-conical end members having their larger ends overlapping the ends of the frame work and secured thereto, propellers at the smaller ends of the end members, means for

operating the propellers from the interior 55 of the end members, and a gas bag disposed in the frame work, and means for adjustably anchoring the ends of the gas bag to the end members, said last mentioned means comprising cross members in the end members and 60 bolts attached to the ends of the gas bag and extending through openings in the cross members and nuts threaded on the bolts so that the ends of the gas bag may be drawn toward said cross members.

65 4. An air ship of the class described comprising a frame work of an ellipsoidal formation, frusto-conical end members having their larger ends overlapping the ends of the frame work and secured thereto, propellers at the 70 smaller ends of the end members, means for operating the propellers from the interior of the end members, and a gas bag disposed in the frame work, said gas bag comprising an ellipsoidal shaped bladder, an ellipsoidal shaped casing about the bladder, and protecting 75 metal noses on the ends of the casing.

80 5. An air ship of the class described comprising a frame work of an ellipsoidal formation, frusto-conical end members having their larger ends overlapping the ends of the frame work and secured thereto, propellers at the smaller ends of the end members, means for operating the propellers from the interior 85 of the end members, and a gas bag disposed in the frame work, said gas bag comprising an ellipsoidal shaped bladder, an ellipsoidal shaped casing about the bladder, and protecting metal noses on the ends of the casing, 90 packing interposed between the noses and the ends of the casing.

95 6. An air ship of the class described comprising a frame work of ellipsoidal formation, a gas bag of ellipsoidal formation in the frame work, metallic noses on the ends of the gas bag having bolts projecting outwardly therefrom through openings in the ends of the frame work, frusto-conical end members on the ends of the frame work having their larger ends overlapping the ends 100 of the frame work, cross members in the end members, means for adjustably anchoring the bolts to the cross members, propellers on the smaller ends of the end members, and means for operating said propellers.

105 In testimony whereof I affix my signature.

PHILIP C. TRAVER.
